FIRE EXTINGUISHING EQUIPMENT

Le Roy Ashmore, Houston, Tex.

Application August 30, 1935, Serial No. 38,787
Renewed March 19, 1938

20 Claims.

(Cl. 169—2)

This invention relates to fire extinguishing equipment and has particular relation to equipment of the character described specially designed for extinguishing the fire of an oil or gas well in case the same should become ignited.

An object of the invention is to provide equipment of the character described which is portable and which may be readily located adjacent a burning well, and is of such form that the workmen may work adjacent the well and at the same time be protected from the intense heat of the fire.

Another object of the invention is to provide equipment of the character described embodying a track, a truck mounted to move along said track, a turret mounted to rotate on a vertical axis on the truck, and having sufficient space therein to contain the workmen, and a boom rotatably mounted on the turret and provided for containing a valve controlled extension pipe and to move the same into alignment with the well pipe for connection to the latter.

Another object of the invention is to provide in equipment of the character described, a turret containing a work chamber for containing the workmen, said turret having surrounding spaces in the walls thereof for circulating water and air, with provision for supplying outside air into the chamber and for relieving said air from the chamber to prevent excess air pressure within the work chamber.

A further object is to provide means whereby the workmen within the chamber may move the turret back and forth along the track or may rotate the turret as well as means whereby the workmen in the chamber may manipulate the boom or the extension pipe therein.

A still further feature resides in the provision of a turret for enclosing and protecting workmen having port holes through which work may be carried on and which may be opened or closed in the usual way.

The invention also comprehends means for circulating the cooling fluid, such as water, through the tracks, as well as through the boom and through the extension pipe housing, provision being made for spraying the equipment with water so as to keep the temperature thereof reduced.

With the above and other objects in view, the invention has particular relation to certain novel features of construction, operation, and arrangement of parts, an example of which is given in this specification and illustrated in the accompanying drawings, wherein:

Fig. 1 shows a side view of the apparatus, partly in section.

Fig. 2 shows a front elevation, also shown partly in section.

Fig. 3 shows a plan view, partly in section.

Fig. 4 shows a fragmentary side view of the extension pipe, partly in section, shown in its relation to the housing and having the inner section of said housing removed, and

Fig. 5 shows a cross-sectional view taken on the line 5—5 of Fig. 2.

Referring now more particularly to the drawings wherein like numerals of reference designate similar parts in each of the figures, the numerals 1, 1, designate suitable tracks which are connected by tubular cross-members 2. As shown in Fig. 2, these tracks may be formed of channel irons spaced apart, but anchored together by the upper and lower transverse webs 3, 4, which may be welded thereto so as to form the enclosed channels 5. The webs 3 are located slightly beneath the upper edges of the channels so as to form the grooves 6 along which the truck wheels hereinafter referred to may move. One end of each track has a hose connection 7 controlled by a suitable valve, as shown, and these connections are provided for the attachment of suitable hose thereto leading from a source of pressure whereby water may be circulated through the tracks and the webs 3 have perforations 8 through which water may be sprayed over said tracks to keep them cool.

The cross-braces 2 are tubular and are connected into the channels 5 whereby water may be circulated through them.

Mounted on the track there is a suitable supporting truck comprising the platform 9 and the wheels 10 arranged to run in the grooves 6. A turret 11 is mounted to rotate on a vertical axis on the truck. This turret may be of any selected shape, but is preferably of a semi-cylindrical contour, as shown in Fig. 3, and is provided with a door 12 for access thereto. This turret is preferably composed of sheet metal, but is lined with asbestos 13, or with similar insulating material. The side walls and top of the turret are surrounded by an air circulating space 14 and outside of this space there is the water circulating space 15 extending around the walls and through the top and bottom of the turret. These spaces may be separated by a partition of asbestos or the like. The turret is of sufficient size to provide a work chamber 16 for containing the workmen, and leading from the air space 14 inwardly into said chamber are the ports 55

17, 17, through which fresh air may continuously enter the work chamber, and said chamber 16 is provided with a relief valve 18 for relieving the air so that the air pressure in the work chamber will not become too great. Air may be admitted into the air chamber 14 through the valve-controlled hose connection 19, and water may be admitted in to the water chamber 15 through the valve-controlled hose connection 20. Suitable metal jacketed hose may be attached to the connections 19, 20, and to a suitable source of supply. The top of the turret is provided with suitable outlet ports 21 through which water from the chamber 15 may be sprayed over 15 the turret.

Fixed on the cross-braces 2, between and in alignment with the tracks 1, is a rack bar 22, and in mesh with the teeth of this bar there is a gear wheel 23 arranged underneath the truck 20 and fixed to a vertical shaft 24 which extends up through the platform 9 and through the bottom of the turret and whose upper end has the handwheel 25 fixed thereon. By rotating the shaft 24, the truck and turret may be moved 25 back and forth on the tracks 1 toward and from the well containing the pipe 26.

Fixed on the platform 9 of the truck there is also a circular rack member 27 and in mesh therewith, there is a spur gear wheel 28 which 30 is fixed on the vertical shaft 29. This shaft extends up through a suitable bearing in the bottom of the turret and has a handwheel 30 fixed thereon within said turret. By a rotation of the handwheel 30, the turret may be suitably rotated about its vertical axis.

The turret may be mounted to rotate on suitable anti-friction bearings 31. Mounted on the top of the turret there is a boom having the circular yoke 32 and the outwardly extended spaced 40 side arms 33, 33, all formed tubular to provide the water circulating channel 34 therethrough. The side arms are connected by the cross-bar 35, also formed tubular. The yoke 32 is mounted to rotate on the bearings 36 which are supported on 45 the race-way 37 on top of the turret, and the yoke is provided with a depending hub 38 which extends down through the top of the turret and has a spur gear wheel 39 fixed thereon. This spur gear wheel is in mesh with a similar smaller gear 50 40 which is fixed on the shaft 41 and fixed on the shaft 41 is a hand wheel 42. By the rotation of the hand wheel 42, the gear 39 and the hub to which it is fixed may be rotated, thus swinging the boom from side to side, as desired.

55 Depending from the side arms 33, 33, are the tubular guides 43, 43, through which the channel 34 also extends whereby water may be circulated through said guides. Between the guides 43, there is a sectional tubular housing designated generally by the numeral 44. This housing is preferably formed of two complementary sections which are arcuate in cross-section, and have the outwardly turned coinciding marginal flanges which may be secured together by the bolts 45. 60 This housing is designed to receive and support an extension pipe 46 to be connected onto the well pipe 26, and this extension pipe may be controlled by a suitable hand-operated valve 47. The housing 44 is shaped to closely surround the pipe 46, and to enclose said valve and is provided with a bearing 48 through which the stem of the valve 47 works. The outer end of said stem has the hand-wheel 49 thereon accessible to the workmen in the turret. At the upper end 65 of the housing 44 there is mounted a pulley 50,

and a cable 51 is attached at one end to the cross-bar 35 and passes around underneath the pulley 50 and over a similar pulley 52 which is mounted on said cross-bar 35 and passes thence over a pulley 53 which is mounted on the yoke 32 and 5 said cable passes thence downwardly through a central vertical bearing in the hub 38 and is wound on a suitable drum 54 which is mounted within the turret and which may be rotated by the crank 55. Through this arrangement, the 10 housing 44 and the extension pipe 46 mounted therein may be elevated and lowered.

The channel 34 has the ports 56 leading upwardly therefrom through which water may be sprayed over the boom, and this channel 34 may 15 be supplied with water from suitable steel jacked hose connected to the hose connection 57.

The housing 44 has oppositely arranged vertical ribs 57, 57, which move between the inwardly extended flanges 58, 58, carried by the guides 20 43, and the ribs are provided with vertical slots 59 through which the rods 60 pass, the ends of said rods being anchored to the flanges 58.

In use, the apparatus is located as near to the burning oil or gas well as conditions will permit, 25 with the track directed toward the well and with the turret at the end of track remote from the well so that it may be readily entered.

The workmen may enter the turret through the door 12 and then propel the turret toward the 30 well, as hereinabove explained. The housing 44 and the extension pipe 46 therein will be maintained in their elevated positions until said extension pipe 46 is swung around into alignment with and above the pipe 26. This may be done 35 by turning the handwheel 42 as hereinabove explained. When the extension pipe 46 is aligned above the well pipe, the extension pipe and housing therefor may be lowered by means of the cable 51, as indicated, until the extension pipe 40 rests upon the upper end of the well pipe. Thereupon the escaping gas or oil will flow up through the extension pipe and the flame will thereafter be at the top of the extension pipe a sufficient 45 distance above the ground to permit workmen to work about the mouth of the well, and the extension pipe may then be welded on to the well pipe, or otherwise connected thereto. When this is done, the valve 47 may be closed and the fire 50 thus extinguished. Any other means for connecting the extension pipe 46 to the well pipe 26 than by welding may be employed in accordance 55 with the circumstances.

The front part of the turret has the transverse window 61 and the port holes 62 beneath said 55 window. These are closed by suitable transparent material which will not be injuriously affected by intense heat. The housing 44 is also preferably formed with inside circulating chambers 64 which may be supplied with water through suitable 60 hose connected to the hose connection 65.

The hose employed for supplying water to the equipment should be flexible to permit free movement of the apparatus and should be steel jacked so as to withstand the heat to which it will 65 be subjected.

When the fire has been extinguished, the housing 44 may be taken apart and readily removed from the extension pipe 46, and the equipment 70 then removed from the location, leaving the well under control.

The drawings and description disclose what is now considered to be a preferred form of the invention by way of illustration only, while the 75

broad principle of the invention will be defined by the appended claims.

What I claim is:

1. Fire extinguishing equipment for oil and gas wells comprising a track, a turret mounted to move along the track and to rotate about a vertical axis, a boom mounted on the turret and extended laterally therefrom and revolvable about the vertical axis, means for circulating a cooling fluid through the turret and boom and means suspended from the boom for connection to the well pipe whereby said well pipe may be closed. 5

2. In equipment of the character described, a turret containing a work chamber and having walls provided with a water circulating chamber and an air circulating chamber about the work chamber. 15

3. In equipment of the character described, a turret containing a work chamber and having walls provided with a water circulating chamber and an air circulating chamber about the work chamber, said air circulating chamber having a port leading into the work chamber, and the work chamber having a valve-controlled relief outlet. 20

4. In equipment of the character described, a turret containing a work chamber and whose walls have a water circulating chamber around the work chamber, the turret having ports leading out from said water circulating chamber, and means for supplying water to said circulating chamber. 25

5. In equipment of the character described, a housing containing a work chamber, the wall of the housing having an air circulating chamber about the work chamber, provided with a port through which air may pass into the work chamber, means for introducing air into said air chamber, said work chamber having a valve-controlled relief outlet. 30

6. A fire extinguishing equipment comprising a track having water circulating channels therethrough provided with discharge ports, a truck mounted to move along said track, a housing mounted to rotate about a vertical axis on said truck and having a work chamber therein, means for propelling the truck along said track, said means being accessible for operation within the work chamber, means for rotating the housing about its vertical axis. 35

7. A fire extinguishing equipment comprising a track having water circulating channels therethrough provided with discharge ports, a truck mounted to move along said track, a housing mounted to rotate about a vertical axis on said truck and having a work chamber therein, means for propelling the truck along said track, said means being accessible for operation within the work chamber, means for rotating the housing about its vertical axis, a boom swingable about a vertical axis and mounted on the turret, a supporting housing for an extension pipe suspended from the boom and means operable from within the work chamber for swinging the boom to move said housing to a selected location. 45

8. Equipment of the character described comprising a track, a housing movable along the track and containing a work chamber, means for circulating cooling fluid about said chamber and a boom mounted on the housing to pivot about a vertical axis. 50

9. Equipment of the character described comprising a track having passageways therethrough for the circulation of a cooling fluid and provided with ports through which the tracks may be 55

sprayed with said fluid, a housing mounted to move along said track and containing a work chamber, means for circulating a cooling fluid about said chamber, said housing having ports through which the housing may be sprayed with said cooling fluid, a boom mounted to pivot about the vertical axis on said housing and having depending guides, said boom and guides having channels for the circulation of the cooling fluid therethrough. 10

10. Equipment of the character described comprising a track having passageways therethrough for the circulation of a cooling fluid and provided with ports through which the track may be sprayed with said fluid, a housing mounted to move along said track and containing a work chamber, means for circulating a cooling fluid about said chamber, said housing having ports through which the housing may be sprayed with said cooling fluid, a boom mounted to pivot about the vertical axis on said housing and having depending guides, said boom and guides having channels for the circulation of the cooling fluid therethrough, a housing vertically movable between said guides and shaped to contain an extension pipe and means accessible for operation within the work chamber and connected to said last-mentioned housing and operative to adjust the same vertically. 15

11. In equipment of the character described, an extension pipe formed with a valve casing and having a valve in said casing, a sectional housing surrounding the extension pipe and shaped to receive the valve casing and having a bearing in which the valve stem may operate. 20

12. In equipment of the character described, an extension pipe formed with a valve casing and having a valve in said casing, a sectional housing surrounding the extension pipe and shaped to receive the valve casing and having a bearing in which the valve stem may operate, said housing being formed with internal channels for the circulation of a cooling fluid therethrough. 25

13. Equipment of the character described comprising a carriage, a housing mounted on the carriage and containing a work chamber, means for circulating a cooling fluid about said chamber, said housing having ports through which the housing may be sprayed with said fluid, a boom mounted to pivot about an approximately vertical axis on the housing and having a depending guide, a housing vertically movable on the guide and shaped to contain an extension pipe and means accessible for operation within the work chamber and connected to said last mentioned housing and effective to adjust the same vertically. 30

14. Equipment of the character described comprising a carriage, a water jacketed housing mounted on the carriage and containing a work chamber, a boom mounted on the housing and having depending guide means, means vertically movable on the guide means and shaped to engage an extension pipe, means accessible for operation within the work chamber and connected to said vertically movable means and effective to move the same vertically. 35

15. In a firefighting machine, a housing containing a work chamber, a water jacket insulating the work chamber, and fire fighting equipment controlled from the housing. 40

16. In a firefighting machine, a housing containing a work chamber, a fluid jacket containing a circulating chamber for a cooling fluid associated with the work chamber, conduits con- 45

nected into the fluid jacket and forming means for supplying fluid to said circulating chamber, and a well control device associated with the housing.

5 17. In a firefighting machine, a housing containing a work chamber, a fluid jacket associated with the work chamber and forming a circulating chamber, conduits leading from the fluid jacket chamber and forming means for supplying water

10 to said circulating chamber and mobile means for supporting the housing, and a fire fighting device controlled from within the housing.

18. In a firefighting machine, a housing containing a work chamber, a fluid jacket associated with the work chamber and enclosing a circulating chamber, conduits connected with the circulating chamber and forming means for supplying water to said circulating chamber, a boom as-

sociated with the housing, and well control equipment associated with the boom.

19. In a firefighting machine, a housing containing a work chamber, a fluid jacket enclosing a circulating chamber around the work chamber, conduits connected into the circulating chamber, means for supplying water to said circulating chamber, mobile means for supporting the housing, a boom associated with the housing, and well control equipment associated with the boom.

10 20. Equipment of the character described comprising a carriage, a housing containing a work chamber mounted on the carriage, a boom mounted on the housing to rotate in a horizontal plane, water and air jackets containing circulating 15 chambers associated with the housing and the boom, guide means depending from the boom and a fire-fighting tool on the guide means.

LE ROY ASHMORE.
